CLAIM

The ornamental design for a knife with integrated moveable guard, as shown and described.

DESCRIPTION

FIG. 1 is an upper perspective view of a knife with integrated moveable guard in closed position.

FIG. 2 is a lower perspective view of the knife with integrated moveable guard in closed position.

FIG. 3 is an upper perspective view of the knife with integrated moveable guard in open position.

FIG. 4 is a lower perspective view of the knife with integrated moveable guard in open position.

FIG. 5 is a left side view of the knife with integrated moveable guard in open position.

FIG. 6 is a left side view of the knife with integrated moveable guard in half open position.

FIG. 7 is a left side view of the knife with integrated moveable guard in closed position, the right side views of which are not shown as they are mirror images of FIGS. 5, 6 and 7 respectively.

FIG. 8 is a top view of the knife with integrated moveable guard in closed position.

FIG. 9 is a top view of the knife with integrated moveable guard in half open position.

FIG. 10 is a top view of the knife with integrated moveable guard in open position.

FIG. 11 is a bottom view of the knife with integrated moveable guard in closed position.

FIG. 12 is a bottom view of the knife with integrated moveable guard in half open position.

FIG. 13 is a bottom view of the knife with integrated moveable guard in open position.

FIG. 14 is a front view of the knife with integrated moveable guard in closed position.

FIG. 15 is a front view of the knife with integrated moveable guard in half open position.

FIG. 16 is a front view of the knife with integrated moveable guard in open position.

FIG. 17 is a rear view of the knife with integrated moveable guard in closed position.

FIG. 18 is a rear view of the knife with integrated moveable guard in half open position; and,

FIG. 19 is a rear view of the knife with integrated moveable guard in open position.

Any broken line showing is for environmental purposes only and forms no part of the claimed design.
